United States Patent Office

Des. 214,602
Patented July 1, 1969

214,602

MAILBOX

Arthur E. Stuker, P.O. Box 937,
San Leandro, Calif. 94577

Filed Apr. 18, 1968, Ser. No. 11,516

Term of patent 14 years

Int. Cl. D31; D3—99

U.S. Cl. D74—9

FIG. 1

FIGURE 1 is a perspective view of a mailbox showing my new design as viewed from the front; and

The undisclosed side of the mailbox in both figures of the drawing is a mirror image of the side illustrated.

I claim:

The ornamental design for a mailbox, substantially as shown and described.
